[57]**CLAIM**

The ornamental design for housing for hand-held electronic data reader, as shown and described.

DESCRIPTION

FIG. 1 is a perspective view of a housing for hand-held electronic data reader, showing my new design;

FIG. 2 is a top plan view thereof;

FIG. 3 is a front elevational view thereof;

FIG. 4 is a right side elevational view thereof;

FIG. 5 is a left side elevational view thereof;

FIG. 6 is a rear elevational view thereof;

FIG. 7 is a bottom plan view thereof; and,

FIG. 8 is a perspective view of a second embodiment of the design shown in FIG. 1, the other sides being identical to the first embodiment except for the oval indentations along the sides.

The broken lines showing hinges throughout the views are for illustrative purposes only and form no part of the claimed design.
